(57) **CLAIM**

The ornamental design for a wearable display device, as shown and described.

DESCRIPTION

FIG. 1 is a front perspective view of a wearable display device according to our design in first configuration;

FIG. 2 is a front elevation view of the wearable display device of FIG. 1;

FIG. 3 is a back elevation view of the wearable display device of FIG. 1;

FIG. 4 is a right elevation view of the wearable display device of FIG. 1;

FIG. 5 is a left elevation view of the wearable display device of FIG. 1;

FIG. 6 is a top elevation view of the wearable display device of FIG. 1;

FIG. 7 is a bottom elevation view of the wearable display device of FIG. 1;

FIG. 8 is a front perspective view of the wearable display device according to the embodiment of FIG. 1 in a second configuration;

FIG. 9 is a right elevation view of the wearable display device of FIG. 8;

FIG. 10 is a front perspective view of the wearable display device according to the embodiment of FIG. 1 in a third configuration;

FIG. 11 is a right elevation view of the wearable display device of FIG. 10;

FIG. 12 is a right elevation view of the wearable display device according to the embodiment of FIG. 1 in a fourth configuration; and,

FIG. 13 is a right elevation view of the wearable display device according to the embodiment of FIG. 1 in a fifth configuration.

Broken lines are environmental only and form no part of the claimed design.
